PENDANT FOR WATCHES AND THE LIKE

Louis L. Burghoff, Bristol, Conn., assignor to The
E. Ingraham Company, Bristol, Conn., a cor-
poration

Application January 30, 1934, Serial No. 708,937

5 Claims. (Cl. 58—95)

This invention relates to improvement in pendants and particularly to pendants for watch cases and the like.

One of the objects of the present invention 5 is to provide a superior pendant construction characterized by strength and economy of manufacture and assembly.

Another object is to provide a superior pendant construction whereby the crown of the 10 watch may be mounted close to the case.

A further object is to provide a pendant construction wherein the exposed portion of the pendant-head makes a neat junction with the exterior surface of the case from which it offsets.

15 Other objects and advantages will appear to those skilled in the art from the following, considered in conjunction with the accompanying drawing and the appended claims.

In the accompanying drawing:

20 Fig. 1 is a face view of a watch equipped with a pendant feature in accordance with the present invention;

Fig. 2 is a face view of the center-band of such a watch stripped, save for the pendant-head bow;

Fig. 3 is a broken view in transverse section taken on the line 3—3 of Fig. 2;

Fig. 4 is a similar sectional view but taken in a central plane paralleling the plane of the center-band;

Fig. 5 is a broken view in horizontal section taken on the line 5—5 of Fig. 2;

Fig. 6 is a broken edge view of the center-band looking toward the head-passage therein;

Fig. 7 is a perspective view of the pendant-head detached; and

Fig. 8 is a similar view of a piece of extruded bar-stock from which the pendant-heads may be formed.

40 As illustrative of the present invention, the pendant-head feature is embodied in a watch having the usual case-member or center-band 10 of outwardly-bowed form in cross-section and having the usual annular snap-shoulders 11 and 12 for the reception respectively of a bezel-ring 13 and a backplate (not shown), in accordance with the usual practice in the watch art.

At the desired point upon its periphery, the center-band 10 above referred to is perforated 50 to form a head-receiving passage 14 leading outwardly therethrough and preferably of polygonal or other non-circular form, as shown especially well in Fig. 6.

Extending outwardly through the head-re- 55 ceiving-passage 14 is a pendant-head 15 having

a horizontal sectional form corresponding to the form of head-receiving-passage 14 in the center-band 10. Offsetting from each of the respective opposite ends of the pendant-head is a stop-lug or abutment 16 adapted to engage the inner surface of the center-band adjacent the respective opposite ends of the passage 14 therein to limit the outward movement of the pendant-head, as will be more fully hereinafter explained.

5 The pendant-head 15 is provided with a central stem-receiving passage 17 in the usual manner of watch-pendants and is also provided in each of its respective opposite end walls with a socket 18 having its axis extending at a right 10 angle to the axis of the stem-receiving passage 17 before referred to.

Pivottally mounted upon the pendant-head 15 is a bow 19 of any approved pattern and having each of its respective opposite ends cylindrically 20 shaped to form a trunnion 20 for entry into one of the sockets 18 of the pendant-head 15. As shown in Fig. 1, a knurled crown 21 is mounted in the space enclosed by the bow 19.

The pendant-head may be formed in a wide 25 variety of ways, but it has been found most economical to employ a bar such as 22, shown

in Fig. 8, which may be readily produced by an extruding operation and has a cross-sectional form corresponding to the horizontal sectional 30 form of the desired pendant-head at a point which will include the stop-lugs 16. The end of such a bar may be first drilled lengthwise to provide the stem-receiving passage 17 and notched at its respective opposite ends to provide the stop-lugs 16 and further laterally drilled in the said notches to provide the sockets 18. The bar may now be severed along the dotted line 23 indicated in Fig. 8, to thus provide 35 a pendant-head ready for installation in the center-band 10.

The installation of the pendant-head is effect- 40 ed by installing the same from the inside of the center-band 10 and projecting its smaller end outwardly through the head-receiving pas- 45 sage 14 in the said center-band until the off-

setting stop-lugs or abutments 16 engage with the inner surface of the center-band adjacent the non-circular head-receiving-passage 14 therein. The bow 19 may now have its comple- 50 mentary trunnions 20—20 installed in the complementary sockets 18—18 of the pendant-head and will serve in such position to prevent, if desired, the pendant-head from falling inwardly into the interior of the center-band 10. Prefer- 55

ably, however, the pendant-head is secured in place by applying solder to the assembly, as indicated at 24.

When installed in place, the offsetting stop-lugs or abutments 16 serve to effectively resist the normal strains upon the pendant-head tending to draw the same outwardly, and the non-circular shape of the projecting portion of the pendant-head, closely fitting, as it does, the passage 14, serves to hold said pendant-head against turning with respect to the center-band 10.

As before pointed out, the pendant-head is shaped to snugly fit the head-receiving-passage 14 in the center-band 10 of the case-member and when installed in place the junction-point between the said pendant-head and the center-band is of neat and workmanlike appearance and gives the impression that the pendant-head is carefully shaped upon its under side to conform to the doubly-curved outer surface of the center-band 10. Furthermore, by means of the present invention, it is unnecessary to perform any delicate and difficult riveting operations from the interior of the center-band in order to insure the firm anchoring of the pendant-head thereto.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. The combination with a case-member having a head-receiving passage opening therethrough; of a pendant-head sized and shaped to pass through and project outwardly from the head-receiving passage in the said case-member beyond the outer surface of the latter and having preformed laterally-offsetting abutment-means engageable with the inner surface of the said case-member to stop the outward movement of the pendant-head through the said head-receiving passage when the pendant-head is assembled with the said case-member by being passed outwardly from the inner end of the said head-receiving passage therein; the said pendant-head having complementary bow-receiving sockets formed directly in the sides of its projecting portion; and a bow having portions entered directly into the bow-receiving sockets of the pendant-head.

2. The combination with a case-member having a head-receiving passage of non-circular form opening therethrough; of a pendant-head substantially corresponding in cross-sectional form to the non-circular form of the said head-receiving passage in the said case-member and installed therein so as to project beyond the outer surface of the said case-member and having preformed laterally-offsetting abutment-means engageable with the inner surface of the said case-member to stop the outward movement of the pendant-head through the said head-receiving passage.

3. The combination with a case-member having a head-receiving passage of non-circular oblong form opening therethrough; of a pendant-head substantially corresponding in cross-sectional form to the non-circular oblong form of the said head-receiving passage in the said case-member and installed therein so as to project beyond the outer surface of the said case-member and having preformed laterally-offsetting abutment-means engageable with the inner surface of the said case-member to stop the outward movement of the said pendant-head through the said head-receiving passage.

4. The combination with a case-member having a head-receiving passage of non-circular oblong form opening therethrough; of a pendant-head substantially corresponding in cross-sectional form to the oblong non-circular form of the said head-receiving passage in the said case-member and installed therein from the inner face of the said case-member so as to project beyond the outer surface thereof and having at each of its respective opposite ends a preformed laterally-offsetting abutment-shoulder engageable with the inner surface of the said case-member to stop the outward movement of the pendant-head through the said head-receiving passage.

5. In a watch-case, the combination with the center-band thereof having a head-receiving passage of non-circular form opening therethrough; of a pendant-head substantially corresponding in cross-sectional form to the non-circular form of the said head-receiving passage in the said center-band and installed therein so as to project beyond the outer surface of the latter and having preformed laterally-offsetting abutment-means engageable with the inner surface of the said center-band to stop the outward movement of the pendant-head through the said non-circular head-receiving passage therein.

LOUIS L. BURGHOFF.
